UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

CRANK-SECTOR SAFETY-ESCAPEMENT FOR ADDING-MACHINES.

1,285,252.

specification of Letters Patent. Patented Nov. 19, 1918.

Application filed April 7, 1916. Serial No. 89,534.

To all whom it may concern:

Be it known that I, WILLIAM W. LASKER, a citizen of the United States, residing in Brooklyn, in the county of Kings and State 5 of New York, have invented certain new and useful Improvements in Crank-Sector Safety-Escapements for Adding-Machines, of which the following is a specification.

This invention relates to perforated card 10 accounting machines in general, and more particularly to machines having type-carrying segments and accumulator wheels co-operating with one another whereby the accumulator wheels accumulate the individual items 15 for which the segments may be set at one time, and for determining the position of the type-carrying segments when totals are to be printed, the type-carrying segments having a series of teeth for cooperating with 20 teeth formed on the accumulator wheels.

In the operation of machines of this type, the type-carrying segments are oscillating members and the accumulator wheels are only actuated into mesh with the type-carrying segments when totals are to be printed or when the individual items are to be accumulated on said accumulator wheels and during the remaining movement of the type carrying segments the accumulator wheels 25 are disengaged from the segments.

When the accumulator wheels are actuated into mesh with the type-carrying segments and the crests of the teeth of the accumulator wheels should strike the crests 30 of the teeth of the type-carrying segments, great strains will be exercised on the several parts of the machine, resulting in the actual destruction of certain of the parts, and not infrequently shearing off the teeth 35 of the type-carrying segments and accumulator wheels.

Among the main objects of the present invention, it is aimed to provide a construction whereby the several parts of the machine 40 will be protected from injury when such faulty engagement takes place.

Other objects of the invention are simplicity of construction and minimum of parts.

These and other features, capabilities and advantages of the invention will appear from the subjoined detail description of one

specific embodiment thereof, illustrated in the accompanying drawings, in which—

Figure 1 illustrates parts of the printing 55 mechanism equipped with the present improvement in which the accumulator wheels are shown free from the type-carrying segments.

Fig. 2 is a fragmental view showing the 60 accumulator wheels and type-carrying segments in faulty engagement with one another while the protecting means receive the strains.

Fig. 3 is a fragmental view showing the 65 accumulator wheels and type-carrying segments in another position of faulty engagement.

Fig. 4 is an end elevational view of the crank sector equipped for the present ar- 70 rangement.

Fig. 5 is an end elevational view of another portion of the protecting means.

In the embodiment shown, there is provided a printing mechanism of the type 75 illustrated in the co-pending application, Serial No. 802,363, filed November 22, 1913, for improvements in tabulator printers, filed in the name of James Powers, having a number of type-carrying segments 11 pro- 80 vided with teeth 12 on their lower edge for engagement with the teeth 13 of the accumulator wheels 14 mounted on the shaft 15 which is slidably guided in the cam slot 16 of the cam levers 17 which are pivotally 85 connected at their lower ends to the shaft 18. The cam levers 17 are pivotally connected to the slide-bar 19 which has an upper actuating notch (not shown) and a lower actuating notch 21. The actuating 90 notches of the slide-bar 19 are adapted to be engaged by the upper and lower actuating pins secured to the actuating lever 22 which is mounted on the shaft 23 on which is actuatedly mounted the lever 24 having a pin 95 25 at its lower end for engagement with the crank sector 26 which is pivotally mounted on the main actuating shaft 27. To the crank sector 26 is pivotally connected the link 28, which in turn is pivotally connected 100 to the retractor 29 for releasing and retracting the type-carrying segments 11.

When the link 19 is drawn into its lower position, it is set for taking totals, which

is done by actuating the total-taking shaft 30 on which is fixed the arm 31 for engaging the upwardly extending arm 32 of the bell crank 33 which is loosely mounted on the 5 shaft 30 and has a forwardly extending arm 34 which is pivotally connected to the slide-bar 19 by the link 35. For normally maintaining the slide-bar 19 in raised position, and therewith the arm 34 in raised position 10 so that the arm 32 rests against the arm 31, the spring 36 is provided.

The operation of the foregoing is substantially as follows:—When individual items are to be printed, the slide-bar 19 being maintained in raised position, the crank sector 26, on its initial forward movement, strikes the pin 25 and carries it forwardly therewith whereby the upper actuating pin on the actuating lever 22 will engage the 15 upper actuating notch of the slide-bar 19 and thrust the slide-bar 19 and the slotted cam lever 17 rearward thereby drawing the accumulator wheels 14 out of engagement with the type-carrying segments 11. Simultaneously therewith the retractor 29, being released by the action of the link 28, the type-carrying segments will travel forward and set type according to the setting of pins not here illustrated. Then, upon the return 20 of the sector 26, the pin 25 being again engaged by the sector, the upper pin of the actuating lever 22 being still in engagement with the upper actuating notch of the slide-bar 19, the slide-bar 19 will again be moved 25 forward thereby moving the accumulator wheels 14 into engagement with the type-carrying segments 11 and thus, upon the return movement of the type-carrying segments 11, the sum printed by the type of 30 such segments, said sum corresponding with the number of segment-teeth that are in advance of the accumulator wheels 14, will be accumulated on the accumulator wheels 14. When a total is to be taken, the shaft 35 30 will be actuated thereby drawing down the slide-bar 19, through the action of the spring 36, so that the lower actuating pin of the actuating lever 22 will engage the actuating notch 21 of the slide-bar 19 upon 40 the actuation of the pin 25 by the sector 26, and then the accumulator wheels 14 will be moved into engagement with the segments 11 upon the forward movement of the crank segment 26, and consequently the released 45 segments will be in mesh with the accumulator wheels 14 on the forward movement and the position of such segments determined by the accumulation on such wheels in the same manner as illustrated and described in the co-pending application, above 50 referred to. Upon the return movement of the sector 26, the accumulator wheels 14 will be withdrawn from free engagement with the segments 11, and consequently the accumulator wheels 14 be thereby cleared. 55

The mechanism forming the protecting means now to be described constitutes the main feature of the present invention. The sector 26 is resiliently connected to the shaft 27, there being positioned adjacent to the 70 sector 26 and fixed to the shaft 27, a bracket 37, which has a pin 38 on its rearward end, and a curved slot 39 forwardly thereof. Through this slot 39 extends the stop pin 40 of the sector 26. Near the front edge 75 of the sector 26 upwardly of the bracket 37 is formed an anchor pin 41. Secured to the anchor pins 41 and 38 is the spring 42 which is substantially resistant, by means of which spring 42 the sector 26 is resiliently carried with the bracket 37 on the return movement of such bracket, the sector 26 being actuated forwardly by the co-operation of one end of the slot 39 with the pin 40. 80

For positively determining the forward and rearward limit of movement of the shaft 27, the stop bracket 43 is provided with a rearwardly extending arm 44 and a forwardly extending arm 45, the rearwardly extending arm 44 being adapted to engage 85 the stop post 46 secured to the main frame A, and the stop arm 45 being adapted to engage the stop post 47 secured to the main frame A. The bracket 43 is also fixed to the shaft 27. 90

The operation of the protecting means is substantially as follows:—Should the accumulator wheels 14 be moved to engage the teeth 12 of the segments 11 and there be any displacement of the accumulator 100 wheels 14, and the teeth 13 of the wheels 14 not properly mesh with the teeth 12 of the segments before their crests engage one another, with the ensuing return movement of the bracket 37, the sector 26 will be obstructed from forward movement, and the spring 42 take up the strain of such faulty engagement as shown in Fig. 2. Obviously the retractor will likewise be estopped from returning when the sector is so obstructed, 105 and consequently none of the type-carrying segments of the particular group will be returned, and therefore no accumulation take place on any of the accumulator wheels until the faulty engagement has been corrected. Thereby not only will the machine parts be protected from injury, but also the record preserved from an erroneous accumulation. 110

It is obvious that various changes and 115 modifications may be made to the details of construction without departing from the general spirit or scope of the present invention.

I claim:

1. The combination, with a printing mechanism having type carrying segments and accumulator wheels for co-operating with said segments, of an actuator shaft; a sector loosely mounted on the actuator 120

shaft; a bracket rigidly mounted on the actuator shaft and provided with an anchor pin; an anchor pin on the sector; a tension spring stretched between said anchor pins; and means operated by the sector for moving the accumulator wheels into and out of engagement with the segments.

2. The combination, with a printing mechanism having type carrying segments and accumulator wheels for coöperating with said segments, of an actuator shaft; a sector loosely mounted on the actuator shaft; a bracket rigidly mounted on the actuator shaft and provided with an anchor pin and a curved slot; a stop pin on said sector and projecting through said slot; an anchor pin on the sector; a tension spring stretched between said anchor pins; and means operated by the sector for moving the accumulator wheels into and out of engagement with the segments.

3. The combination, with a printing mechanism having type carrying segments and a retractor for releasing and retracting the segments, of accumulator wheels adapted to coöperate with said segments; an actuator shaft; a sector loosely mounted on said actuator shaft; a bracket rigidly mounted on the actuator shaft and provided with a curved slot and an anchor pin; a stop pin provided on said sector and projecting through said slot; an anchor pin on the sector; a tension spring connecting said anchor pins; and means adapted to be contacted by the sector for moving the accumulator wheels into and out of coöperation with the type carrying segments.

4. The combination, with a printing mechanism having type carrying segments and a retractor for releasing and retracting the segments, of accumulator wheels adapted to coöperate with said segments; an actuator shaft; a sector loosely mounted on said shaft; a bracket rigidly mounted on the shaft and provided with a curved slot and an anchor pin; a stop pin provided on said sector and projecting through said slot; an anchor pin on said sector; a tension spring connecting said anchor pins; an additional bracket rigidly mounted on said shaft and provided with stop arms; adjustable stop posts adapted to be engaged by said arms respectively to limit the movement of the shaft; and means adapted to be contacted by the sector for moving the accumulator wheels into and out of cooperation with the type carrying segments.

5. The combination, with a printing mechanism having type carrying segments

and a retractor for releasing and retracting the segments, of accumulator wheels adapted to coöperate with said segments; an actuator shaft; a sector loosely mounted on said actuator shaft; a bracket rigidly mounted on the actuator shaft and provided with a curved slot and an anchor pin; a stop pin provided on said sector and projecting through said slot; an anchor pin on said sector; a tension spring connecting said anchor pins; a link having its ends pivoted to the retractor and said sector respectively; and means adapted to be contacted by the sector for moving the accumulator wheels into and out of coöperation with the type carrying segments.

6. The combination, with a printing mechanism having type carrying segments and a retractor for releasing and retracting the segments, of accumulator wheels adapted to coöperate with said segments; an actuator shaft; a sector loosely mounted on said shaft; a bracket rigidly mounted on the shaft and provided with a curved slot and an anchor pin; a stop pin provided on said sector and projecting through said slot; an anchor pin on the sector; a tension spring connecting said anchor pins; an additional bracket rigidly mounted on said shaft and provided with stop arms; adjustable stop posts adapted to be engaged by said arms respectively to limit the movement of the shaft; a link having its ends pivoted to the retractor and said sector respectively; and means adapted to be contacted by the sector for moving the accumulator wheels into and out of coöperation with the type carrying segments.

7. In combination with a printing mechanism having oscillating type-carrying segments, accumulator wheels, a main driving shaft, a crank sector mounted on said shaft, resilient means for connecting said sector with said shaft, connecting means for connecting said sector with said wheels so that the actuation of said sector will actuate said wheels, the resilient means taking up the strain in case of faulty engagement between said wheels and said segments, a stop member fixed on said bracket, two stop arms extending from said stop member, and stop posts to either side of said driving shafts, said posts and arms engaging one another to determine the extreme positions of said bracket.
